[57] CLAIM

The ornamental design for a front panel for a mobile radio,
as shown and described.

DESCRIPTION

FIG. 1 is a top plan view of a front panel head for a mobile
radio showing our new design, the broken line shown is for
illustrative purposes only, and forms no part of the claimed
design;

FIG. 2 is a front elevational view;

FIG. 3 is a bottom plan view;

FIG. 4 is a left side elevational view;

FIG. 5 is a right side elevational view; and,

FIG. 6 is an enlarged front, top, and left side perspective
view thereof.
